DESIGN.

No. 35,130.

Patented Sept. 24, 1901.

J. ALLISON.

POST TAMPER.

(Application filed Aug. 14, 1901.)

UNITED STATES PATENT OFFICE.

JOHN ALLISON, OF INDEPENDENCE, MISSOURI.

DESIGN FOR A POST-TAMPER.

SPECIFICATION forming part of Design No. 35,130, dated September 24, 1901.

Application filed August 14, 1901. Serial No. 72,079. Term of patent 14 years.

To all whom it may concern:

Be it known that I, JOHN ALLISON, a citizen of the United States, residing at Independence, in the county of Jackson and State of Missouri, have invented and produced a new and original Design for a Post-Tamper, of which the following is a specification.

This invention relates to a new and original design for a post-tamper; and the essential features reside in the design as illustrated in the accompanying drawings, wherein—

Figure 1 is a perspective view of a post-tamper embodying the design. Fig. 2 is an end elevation of the same.

The design is characterized by a rectangular base or head 1, from which rises a conically-shaped projection 2, converging toward its upper end and having a concave surface. Extending upwardly from the upper end of the projection 2 is a cylindrical bar 3, which connects at its upper end with the lower reduced extremity 4 of a blade 5, having opposite flat faces 6, which converge inwardly to-

ward an upper straight end 7, the latter being flat. At the upper portion of the opposite ends of the blade are parallel flat faces 8 to intersect the end 7 in planes at right angles to the latter. From the lower limits of the faces 8 the opposite side portions of the blade converge in concave planes, as at 9, toward the lower reduced extremity 4 of said blade.

Having thus described the invention, what is claimed as new is—

The design for a post-tamper, herein shown and described.

In testimony that I claim the foregoing as my own I have hereto affixed my signature in the presence of two witnesses.

JOHN ^{his} X ALLISON.
